In the Netherlands October 22, 1936

12 Claims. (Cl. 179—171)

The invention relates to an amplifying system for modulated high frequency oscillations, which is particularly suitable for the final stage of a transmitter.

5 It is known to utilize for the amplification of modulated high frequency oscillations an amplifying tube wherein the grid bias has such a value that the tube passes current only during one half wave of the alternating voltage to be amplified. 10 Such an amplifier is known under the name of "Class B amplifier" and with full load it has an efficiency of

$$\frac{\pi}{4}$$

15 if the amplitude of the alternating voltage set up in the output circuit is assumed to be equal to the direct anode voltage. In practice, however, a maximum anode alternating voltage is allowed which is equal to 0.8 to 0.9 times the direct anode 20 voltage with the result that the maximum efficiency of a class B amplifier is in practice not higher than 0.8 to 0.9 times

$$\frac{\pi}{4} = \text{about } 67\%$$

25 When such an amplifier is employed for the amplification of modulated high frequency oscillations this efficiency of 67% only occurs with 100% modulation of the carrier wave whereas the 30 efficiency of the amplification of the unmodulated carrier wave cannot be higher than about 33%. For broadcast transmitters the average percentage of modulation over an entire day is very small while the instantaneous value of the percentage 35 of modulation seldom surpasses 30%, or in other words the efficiency of a class B amplifier is on the average not much higher than 33%.

In describing my invention in detail reference will be made to the attached drawing wherein, 40 Figures 1 and 2 illustrate fundamental circuit arrangements utilizing the principle of my invention, while

45 Figures 3 and 4 illustrate modifications of the arrangements of Figures 1 and 2, and,

45 Figure 5 illustrates details of the arrangement of Figure 4.

In order to obtain a higher efficiency it has previously been proposed to utilize the system shown in Figure 1. In this system 1 denotes a 50 class B amplifier which is loaded by an impedance which behaves for the frequency of the carrier oscillation as an ohmic resistance of the value 2R. The output circuit of the amplifier 1 comprises the output terminals 5 and 6 of a network 55 7 while the input terminals 8 and 9 are con-

nected to an amplifier 2 whose bias voltage is chosen in such manner that this amplifier only passes current if the amplitude of the oscillations to be amplified surpasses that of the carrier oscillation. The oscillations to be amplified are supplied to the amplifiers 1 and 2 with a mutual phase displacement of 90°. The network 1 is constructed to have the reversible property that the impedance occurring across the output terminals 5 and 6 is inversely proportional to the impedance connected between the input terminals 8 and 9. The product of said impedances is R_0^2 where $R_0 = R$ and is hereinafter referred to as "surge impedance."

5 So long as the amplifier 2 is not conductive, 15 or in other words the amplitude of the oscillations to be amplified is smaller than the carrier wave amplitude, the impedance occurring across the terminals 5 and 6 will be zero and the amplifier 1 will be loaded by the resistance 2R. If the 20 amplitude of the oscillations to be amplified surpasses the carrier wave amplitude the amplifier 2 becomes conductive during that portion of the 25 oscillations to be amplified wherein the instantaneous value of the oscillations surpasses the carrier wave amplitude while across the terminals 5 and 6 a negative resistance occurs which in the case of maximum conductivity of the amplifier 2, which occurs at the peak voltage of a 30 100% modulated carrier oscillation, is equal to

$$\frac{R_0^2}{R} = R$$

The load of the amplifier 1 consequently depends 35 on the instantaneous value of the oscillations to be amplified in such manner that the load amounts to 2R as long as the amplitude of the oscillations to be amplified is smaller than the amplitude of the unmodulated carrier oscillation, whereas the load is reduced from 2R to R if the 40 instantaneous value of the oscillations to be amplified increases to the peak voltage of the 100% modulated carrier wave, i. e., to a value which is equal to twice the carrier wave amplitude. The 45 load of the amplifier 2 is determined by the impedance connected between the terminals 5 and 6, which impedance is determined by the conductivity of the amplifier 1. The circuit arrangement of the amplifier 1 is so chosen that if the instantaneous value of the oscillations to be amplified increases from the carrier wave amplitude to double this value, the negative resistance presented by the amplifier 1 decreases from 2R to R and consequently the resistance present between 50 the terminals 5 and 6 increases from 0 to R. The 55

load of the amplifier 2 consequently decreases, when the instantaneous value of the oscillations to be amplified increases from the carrier wave amplitude to the peak value of the voltage of the 100% modulated carrier from ∞ to R.

The system described operates as follows:

So long as the amplitude of the oscillations to be amplified which are supplied to the amplifiers 1 and 2 is lower than the carrier wave amplitude, the amplifier 2 is blocked and the amplifier 1 is loaded by a resistance $2R$ which is so chosen that the highest allowable anode alternating voltage of the amplifying tubes is attained when the amplitude of the oscillations to be amplified is equal to the unmodulated carrier wave amplitude. The efficiency of the amplifier 1, which increases with an increasing amplitude of the oscillations to be amplified, has consequently attained with unmodulated carrier wave amplitude its maximum value of 67%. When the amplitude of the oscillations to be amplified surpasses that of the unmodulated carrier wave, the amplitude of the alternating voltage set up in the output circuit of the amplifier 1 can no longer increase and, but for the presence of the amplifier 2, the output energy of the amplifier would increase no longer. At this moment, however, the amplifier 2 becomes conductive with the result that the load resistance of the amplifier 1 decreases and an increase of the output energy of the amplifier 1 can be obtained by an increase of the anode current of the amplifying tubes without any increase of the anode alternating voltage, which has already attained its maximum value. At the maximum voltage of the 100% modulated carrier oscillation the load of the amplifier 1 is equal to R while the output energy of the amplifier 1 is twice as large as in the amplification of an unmodulated carrier oscillation. At the peak value of the voltage of the 100% modulated carrier oscillation the load of the amplifier 2 is also equal to R while the energy supplied by this amplifier is equal to the energy delivered by the amplifier 1. The total output energy of the amplifiers 1 and 2 is consequently equal to four times the output energy of the amplifier 1 during the amplification of an unmodulated carrier oscillation.

When a 100% modulated carrier oscillation is amplified, the efficiency of the amplifier 1 is slightly smaller than with an unmodulated carrier oscillation, for example 50%, while the efficiency of the amplifier 2, which acts as a class C amplifier, is higher, for example 80%. With 100% modulation the efficiency of the total system is consequently approximately as high as with unmodulated carrier wave. With respect to the usual class B amplifiers the system described consequently offers the advantage that the average efficiency over an entire day is considerably higher. In contradistinction to that which is the case with class B amplifiers this efficiency is, however, always lower than the efficiency obtained when an unmodulated carrier wave is amplified.

Figure 2 represents a system which is completely dual to the system described and which functions in a similar way. With this system the amplifier 1 is connected to a load resistance

$$\frac{R}{2}$$

via a network 7 which has the same property as the network 1 in Figure 1. The amplifier 2 is connected to the ends of this resistance and possesses a bias voltage such that current is only

passed when the amplitude of the oscillations to be amplified surpasses the carrier wave amplitude. The surge impedance R_0 of the network 7 amounts to R.

During the amplification of the unmodulated carrier wave the amplifier 2 is unoperative while the amplifier 1 is loaded by an impedance

$$\frac{R_0^2}{R} = 2R$$

If the instantaneous value of the oscillations to be amplified increases to above the carrier wave amplitude, the amplifier 2 becomes conductive so that in parallel with the load resistance

$$\frac{R}{2}$$

is connected a negative resistance which amounts at the maximum voltage of the 100% modulated carrier oscillation to R with the result that the amplifier 1 is loaded by a resistance

$$\frac{R_0^2}{R} = R$$

When the instantaneous value of the oscillations to be amplified increases from the carrier wave amplitude up to the maximum voltage of the 100% modulated carrier oscillation, the load of the amplifier 2 decreases from ∞ to R.

The operation of this system further corresponds completely to that of the system according to Figure 1, while a more detailed discussion of the system appears in the publication by Doherty at page 1163 of the September, 1936, I. R. E.

The invention concerns an improvement in a system which operates on the principle of the systems shown in Figures 1 and 2.

According to the invention, for the amplification of modulated high frequency oscillations use is made of four amplifiers of which one amplifier (1) passes current, with any amplitude of the alternating voltage supplied, during one half wave whereas the other amplifiers only pass current if the amplitude is located above a predetermined threshold value which is for one of these amplifiers (2) lower and for the two other amplifiers (3 and 4) mutually equal and larger than the carrier wave amplitude while a load impedance is connected in series or in parallel with an impedance to which a voltage is supplied by the first mentioned amplifier (1) or the second amplifier (2). This series or parallel connection is connected to the output terminals of a network having connected to its input terminals an impedance across which the second amplifier (2) or the first amplifier (1) set up a voltage while each of the said impedances is connected in series with the output impedance of a network to the input terminals of which are connected the third and the fourth amplifier (3 and 4) respectively. All these networks possess the property that the input impedance is inversely proportional to the impedance connected between the output terminals while the surge impedance of the latter two networks is equal to half the surge impedance of the first mentioned network, which surge impedance is equal respectively to half or double the load impedance while the oscillations to be amplified are supplied to the grid of the four amplifiers with a phase such that the voltages supplied by these tubes to the load impedance are mutually in phase.

The invention will be explained more fully with

reference to Figures 3 and 4 of the drawing which represent two embodiments thereof.

Figure 3 represents a system which may be considered as an extension of the system according to Figure 1. In this figure, 1 denotes a class B amplifier which is loaded by a resistance $2R$. In the output circuit of the amplifier are located the terminals 5 and 6 of a network 7 to the input terminals of which is connected an amplifier 2 whose bias voltage is chosen in such manner that this amplifier only passes current if the amplitude of the oscillations to be amplified surpasses a predetermined value which is smaller than the carrier wave amplitude. In the circuit which comprises the amplifier 1, the load resistance $2R$ and the terminals 5 and 6, is included the output impedance of a network 11 which has connected to its input terminals an amplifier 4 of which the bias voltage is so chosen that this amplifier only passes current if the amplitude of the oscillations to be amplified surpasses a predetermined value which is greater than the carrier wave amplitude. In the circuit which comprises the amplifier 2 and the terminals 8 and 9 of the network 7 is included the output impedance of a network 10 which has connected to its input terminals an amplifier 3 whose bias voltage is equal to that of the amplifier 4. The networks 7, 10 and 11 possess the property that the input impedance is inversely proportional to the impedance connected between the output terminals, the said property being reversible. The surge impedance R_0 of the network 7 amounts to R while those of the networks 10 and 11 are

$$\frac{R}{2}$$

Since each of the networks 7, 10 and 11 brings about a phase displacement of 90° the high frequency alternating voltages supplied to the input circuits of the amplifiers 2, 3, and 4 are displaced in phase by 90° , 180° and 90° respectively with respect to the voltage supplied to the amplifier 1.

If an unmodulated carrier oscillation is supplied to the amplifiers, the amplifier 1 is operative during the full wave and the amplifier 2 only during part of the wave. During that part of the wave in which the amplifier 2 is not conductive, the amplifier 1 is loaded by a resistance $2R$. At the moment when the amplifier 2 becomes conductive, the instantaneous value of the voltage set up in the output circuit of the amplifier 1 attains its highest admissible value so that the amplifier 1 functions at this moment with the maximum efficiency. During the wave portion wherein the amplifier 2 is conductive, the load of the amplifier 1 is smaller than $2R$ owing to which an increase of the anode current of the amplifying tubes is possible without any increase of the anode alternating voltage.

At the moment when the amplifiers 3 and 4 become conductive, the anode alternating voltage of the tube of the amplifier 2 has attained its highest value permissible and the load of the amplifier 1 is equal to R while furthermore the load of the amplifier 2 amounts to R . At this moment the amount of energy furnished by each of the two amplifiers 1 and 2 is equally large. If the instantaneous value of the oscillations to be amplified surpasses the threshold value of the amplifiers 3 and 4, the load on the amplifiers 1 and 2 decreases due to the fact that a negative resistance occurs between the output terminals of the network 11 or 10 respectively. The negative resistance increases in accordance

with the output of amplifiers 3 and 4. At the maximum voltage of the 100% modulated carrier wave this negative resistance has attained its maximum value ($-\frac{1}{2}R$) and the amplifiers 3 and 4 supply maximum energy while the load of the amplifiers 1 and 2 has decreased from the value R to the value $\frac{1}{2}R$. Owing to the increase of the anode currents of the tubes of the amplifiers 1 and 2, the output energy of these amplifiers has increased to double the value at the moment when the threshold value of the amplifiers 3 and 4 is being surpassed. At the maximum voltage of a 100% modulated carrier oscillation the amplifiers 3 and 4 are each loaded with a resistance

$$\frac{R_0^2}{R} = \frac{1}{2}R$$

since the surge impedance R_0 of the networks 10 and 11 amounts to

$$\frac{R}{2}$$

At this moment each of the amplifiers 1, 2, 3 and 4 delivers an equally large amount of energy and the efficiency of the whole of the installation is equal to the maximum efficiency of a class B amplifier which furnishes the same output energy.

A particular advantage of the system according to the invention resides in that at the most usual values of the percentage of modulation, which are located between 0 and 30% the amplifiers 1 and 2 are continuously in operation, owing to which discontinuities due to the tube 2 being switched on and off are avoided. A further advantage consists in that at the most usual values of the percentage of modulation there occurs a linear relation between the amplitudes of the oscillations to be amplified and the current passing through the load resistance. Besides, in the system according to the invention the average efficiency over an entire day is substantially equal to the efficiency with unmodulated carrier oscillation, said efficiency being approximately 67%.

Figure 4 represents a system according to the invention which is completely dual to the system according to Figure 3 and functions in a similar manner. In this system the amplifier 1 is connected to a load impedance

$$\frac{R}{2}$$

via a network 7 which possesses the same property as the network 7 in the system of Figure 3. The amplifier 2 is connected to the ends of this impedance. The surge impedance of the filter 7 amounts to R . In the circuit which comprises the amplifier 1 and the terminals 8 and 9 of the network 7 is included the output impedance of the network 11 whose surge impedance amounts to

$$\frac{R}{2}$$

and to the input terminals of which is connected the amplifier 4. In the circuit which comprises the amplifier 2 and the load resistance

$$\frac{R}{2}$$

is included the output impedance of a network 10 whose surge impedance also amounts to

$$\frac{R}{2}$$

- and whose input terminals have connected to them the amplifiers 3. The bias voltages and the mutual phase displacements of the oscillations supplied to the input circuits of the amplifiers 1, 2, 3 and 4 are the same as in the system according to Figure 3. The variation of the load resistances of the different amplifiers as a function of the modulation is also completely equal to that in the system according to Figure 3.
- 10 Figure 5 represents one mode of execution of the system according to Figure 3. In this system the amplifier 1 is constituted by a discharge tube 21 to the control grid of which are supplied the oscillations to be amplified and in the anode circuit of which is included a parallel circuit 31 which is tuned to the carrier wave frequency and which is coupled with an inductance 41 which forms jointly with a condenser 51 an impedance across which a voltage is set up by the amplifier 1. The amplifier 2 comprises a discharge tube 22 to which the oscillations to be amplified are supplied with a phase displacement of 90° and whose anode circuit comprises a parallel circuit 32 which is coupled with a series circuit consisting of an inductance 42 and a condenser 52. The filter 7 consists of two equal condensers 57 and 57' and an inductance coil 47, while the two condensers are connected in series between the terminals 5 and 8 and the junction point of the condensers is connected via the inductance 47 to the terminals 6 and 9. The networks 10 and 11 consist each of two coupled inductances 43, 43' and 44, 44' respectively of which the inductances 43 and 44 respectively are connected in series with condensers 53 and 54 respectively and the other inductances 43' and 44' respectively are connected in series with condensers 53' and 54' respectively between the output terminals, said two series connections being tuned to the carrier wave. The amplifiers 3 and 4 comprise each a discharge tube 33 and 34, respectively, to which the oscillations to be amplified are supplied with a phase displacement of 180° and 90° respectively and in the anode circuit of which is included the input impedance of the filter 10 and 11 respectively.
- 15 In the system described the condensers 51, 54' and 57, which are located in the same circuit, may be combined to form a single condenser; the same remark applies to the condensers 52, 53' and 57'.
- 20 The system according to Figure 4 may be formed in an analogous manner.
- 25 It is evident that the amplifiers 1, 2, 3 and 4 may each comprise any desired number of amplifying tubes connected in cascade while one or more stages of this cascade may consist of two push-pull connected amplifying tubes.
- 30 If either of the amplifiers 3 and 4 should be rendered ineffective the system will operate with only the remaining amplifiers. Appropriate adjustment of the amounts of power fed into the amplifiers and of the bias of the amplifiers should be made in the manner suggested for the heretofore known systems in the above mentioned IRE publication so that the load will be divided in an equitable manner.
- 35 I claim:
- 40 1. A system for amplifying modulated high frequency oscillations which is particularly suitable for the final stage of a transmitter and which comprises four amplifiers each having an input and an output circuit, the first said amplifier being adjusted to pass current with any amplitude
- 45 of alternating voltages applied thereto during one

half wave, whereas the other amplifiers are adjusted to pass current only if the amplitude is located above a predetermined threshold value which is for the second of these amplifiers lower and for the third and fourth amplifiers mutually equal and larger than the carrier wave amplitude, a plurality of networks having input and output terminals and each having the property that the input impedance is inversely proportional to the impedance connected between the output terminals, a load impedance connected in series with the outputs of the first and second of said networks and an impedance to which a voltage is supplied by said first amplifier, the surge impedance of said first mentioned network being equal to half the load impedance and having connected to its input terminals a series connection of an impedance across which a voltage is set up by said second amplifier and the output of a third network having its input terminals connected to said third amplifier, the input terminals of said second network being connected to the fourth amplifier, the surge impedance of said second and third networks being half that of the first network, said oscillations to be amplified being supplied to the inputs of the four amplifiers in such phase relationship that the voltages supplied by the amplifiers to the load impedance are mutually in phase.

2. A system as claimed in claim 1, wherein the said impedances across which voltages are set up by the first and the second amplifier consist each of the series connection of an inductance and a condenser, said inductance being coupled with a parallel resonant circuit included in the output circuit of the amplifier and which is tuned to the carrier wave.

3. A system as claimed in claim 1, wherein the first mentioned network consists of two condensers and an inductance, said condensers being connected in series between one of the input terminals and one of the output terminals whereas the inductance is located between the junction point of the condensers and the two other terminals.

4. A system as claimed in claim 1, wherein the networks to the input terminals of which are connected the third and the fourth amplifier respectively comprise each two coupled inductances of which one is connected in series with a condenser between the input terminals and the other in series with a condenser between the output terminals, both these series connections being tuned to the carrier wave.

5. In a modulated carrier wave amplifying system, an amplifier which is biased to operate class B, a second amplifier biased to pass current when excited by waves of an amplitude less than the mean carrier amplitude, a third amplifier biased to pass current when excited by waves of an amplitude greater than said mean carrier wave amplitude, means for applying modulated carrier wave energy to said amplifiers, and circuits interconnecting said amplifiers to a load impedance in a mutual in phase relationship, said circuits including networks having inputs and outputs, the impedance at the inputs of said networks being inversely proportional to the impedance at the output thereof.

6. In a modulated carrier wave amplifying system, a first amplifier biased to operate class B, a second amplifier biased to pass current when excited by waves of an amplitude less than the mean carrier wave amplitude, a third amplifier biased to pass current when excited by

waves of an amplitude greater than said mean carrier wave amplitude, means for applying modulated carrier wave energy to said amplifiers, the phase of the wave energy applied to at least one of said amplifiers being displaced 90° relative to the phase of the wave energy applied to another of said amplifiers, and circuits interconnecting said amplifiers to a load impedance in a mutual in phase relationship, said circuits including networks having inputs and outputs, the impedance at the inputs of said networks being inversely proportional to the impedance at the output thereof.

7. In a modulated carrier wave amplifying system, a first amplifier biased to operate class B, a second amplifier biased to pass current when excited by waves of an amplitude less than the mean carrier wave amplitude, a third and a fourth amplifier biased to pass current when excited by waves of an amplitude greater than said mean carrier wave amplitude, means for applying modulated carrier wave energy to all of said amplifiers, the wave energy applied to said second and fourth amplifiers being displaced 90° relative to the wave energy applied to said first amplifier and the carrier wave energy applied to said third amplifier being displaced 180° relative to the phase of the carrier wave applied to said first amplifier and circuits interconnecting said amplifiers to a load impedance in a mutual in phase relationship, said interconnecting circuits including networks having inputs and outputs, the impedance at the inputs of said networks being inversely proportional to the impedance at the output thereof.

8. A system for amplifying modulated high frequency oscillations which is particularly suitable for the final stage of a transmitter and which comprises four amplifiers each having an input and an output circuit, the first said amplifier being adjusted to pass current with any amplitude of alternating voltages applied thereto during one half wave, whereas the other amplifiers are adjusted to pass current only if the amplitude is located above a predetermined threshold value which is for the second of these amplifiers lower and for the third and fourth amplifiers mutually equal and larger than the carrier wave amplitude, a plurality of networks having input and output terminals and each having the property that the input impedance is inversely proportional to the impedance connected between the output terminals, a load impedance connected in series with the outputs of the first and second of said networks and the output of said first amplifier, a series connection of the output of said second amplifier and the output of a third network having its input terminals connected to said third amplifier connected to the input of said first network, the input terminals of said second network being connected to the fourth amplifier, said oscillations to be amplified being supplied to the inputs of the four amplifiers in such phase relationship that the voltages supplied by the amplifiers to the load impedance are mutually in phase.

9. A system for amplifying modulated high frequency oscillations which is particularly suitable for the final stage of a transmitter and which comprises four amplifiers each having an input and an output circuit, the first said amplifier being adjusted to pass current with any amplitude of alternating voltages applied thereto during one half wave, whereas the other amplifiers are adjusted to pass current only if the

amplitude is located above a predetermined threshold value which is for the second of these amplifiers lower and for the third and fourth amplifiers mutually equal and larger than the carrier wave amplitude, a plurality of networks having input and output terminals and each having the property that the input impedance is inversely proportional to the impedance connected between the output terminals, a load impedance connected in series with the outputs of the first and second of said networks and the output of said first amplifier, the surge impedance of said first mentioned network being equal to half the load impedance and having connected to its input terminals a series connection of the output of said second amplifier and the output of a third network having its input terminals connected to said third amplifier, the input terminals of said second network being connected to the fourth amplifier, the surge impedance of said second and third networks being half that of the first network, said oscillations to be amplified being supplied to the inputs of the four amplifiers in such phase relationship that the voltages supplied by the amplifiers to the load impedance are mutually in phase.

10. A system for amplifying modulated high frequency oscillations which is particularly suitable for the final stage of a transmitter and which comprises four amplifiers each having an input and an output circuit, the first said amplifier being adjusted to pass current with any amplitude of alternating voltages applied thereto during one half wave, whereas the other amplifiers are adjusted to pass current only if the amplitude is located above a predetermined threshold value which is for the second of these amplifiers lower and for the third and fourth amplifiers mutually equal and larger than the carrier wave amplitude, a plurality of networks having input and output terminals and each having the property that the input impedance is inversely proportional to the impedance connected between the output terminals, a load impedance connected across the output of one of said networks, the surge impedance of said load being equal to half that of each of the said networks, a series connection of the output circuit of the second of said amplifiers and the output of a second of said networks connected in shunt across said load impedance, the output circuit of the third of said amplifiers being connected across the input terminals of said second network, a series connection of the output of the first of said amplifiers and the output of the third of said networks connected to the input of said first network, the output of the fourth of said amplifiers being connected to the input of said third network, said oscillations to be amplified being supplied to the inputs of said amplifiers in such phase relationship that voltages supplied to the load impedance are mutually in phase.

11. In combination, a first and second amplifier each having input and output circuits, a plurality of impedance inverting networks each having an input and an output, connections from the output circuits of said amplifiers to the input and output respectively of one of said networks, each of said connections including the output circuit of another of said networks, a third and a fourth amplifier each having an input circuit and an output circuit, said output circuits being connected to the input of said last mentioned networks, a load impedance connected

to the output of said one network and means for applying modulated carrier wave energy to the inputs of each of said amplifiers.

12. In combination, a first and second amplifier each having input and output circuits, a plurality of impedance inverting networks each having an input and an output, connections from the output circuits of said amplifiers to the input and output respectively of one of said networks, each of said connections including the output circuit of another of said networks, a

third and a fourth amplifier each having an input circuit and an output circuit, said output circuits being connected to the input of said last mentioned networks, a load impedance connected to the output of said one network and means for applying modulated carrier wave energy to the inputs of each of said amplifiers in such phase relationship that the voltages supplied by the amplifiers to the load impedance are mutually in phase. 10
